FILAMENT CLAMPING DEVICE FOR AN AUTOMATIC MOUNTING MACHINE

Law Lamar Armstrong and Houston D. Carson, Little Rock, Ark., assignors to Westinghouse Electric Corporation, East Pittsburgh, Pa., a corporation of Pennsylvania

Application March 9, 1953, Serial No. 341,308

2 Claims. (Cl. 140—71.6)

The present invention relates to the manufacture of incandescent lamps and, more particularly, to a coil clamping device for automatic filament mounting machines.

In the automatic mounting of incandescent lamp filaments, particularly those for lamps of higher wattage, the larger filaments, for example, coiled coil, employed therein are inherently brittle. This brittleness results in excessive lamp and mount shrinkage due to filament or coil leg fractures in the filament lead clamps during the automatic filament feeding and clamping operation. The leg or legs of the filament break either immediately during the clamping operation, or later in the lamp fabrication between the sealing operation and final inspection. It is also possible that some lamps having fractured coils get into packed production, thus constituting a serious quality problem.

Many attempts, such as the rejection of an entire lot of brittle filaments, have been employed in the past to eliminate this quality problem. Even after an expensive inspection operation such as this, the mount shrinkage remains excessive at a figure of fifty to one hundred mounts per day.

The mounting of a coiled coil filament is conventionally accomplished on an automatic mounting machine having a plurality of lamp stem heads, for example 20, carried on a carrier or turret which is indexable from station to station. At station "1" a stem, positioned at the proper height, is delivered by a conveyor to a stem holding head. The lead wires may be spread at station "2," trimmed to length at station "3" and flattened at station "4." At station "5" the coil clamping hooks are formed in the downward depending extremities of the lead wires. A coiled coil is delivered by automatic transfer means at station "6" and clamped in the hooks formed in the ends of the lead wires. It will be understood that the above mentioned fractures of the coil occurs at station "6," the coil feeding and clamping station. The leads, carrying the filament, are pushed backwardly at station "7" so that the leads pass behind the protective covering of a baffle which extends from stations "8" to "12," the arbor heating and plasticizing stations. The end of the arbor is preheated at stations "8" and "9" and a button is preformed thereon at station "10." Oxygen fires at station "11" raise the temperature of the preformed arbor button to the proper molding temperature. A plurality of support wires, for example three, are horizontally inserted in the plastic button at station "12." The center support wire is "wiped" (that is moved downwardly) at station "13." At station "14" the lead wires are pushed forward to their normal position and the ends of the three supports are suitably pre-curved, or partially formed, in the shape of open hooks. The open hooks of the two horizontal supports may be clamped about the lead wires at station "15." At station "16" the center support wire is hooked about the filament and the mount is finally positioned axially at station "17." If the mount is to be getter dipped, getter is applied at station "18," and dried

2

by suitable heating means at station "19." The finished mount is then unloaded at station "20" onto a suitable conveyor and delivered to an automatic sealing and exhaust machine.

Hence, it has been found advantageous according to our invention to employ two small heaters at station "6," the coil delivery and clamping station, to blow the hot gases of combustion on the coils and clamps during the clamping operation. These gas burners burn into funnels appended thereto, for heating the hooks on the leads, the filament carried by the hooks, and the clamping block by conduction, convection and radiation from the funnelled combustion gases during the clamping operation. The desired amount of heat can be obtained by varying the gas and air mixture fed to the burners.

In its general aspect, the present invention has as its objective the elimination of the defects of prior art clamping devices for automatic incandescent lamp filament mounting machines.

A specific object of the present invention is an improved clamping device which reduces fractured coil shrinkage and improves lamp quality.

Another specific object is an improved clamping device comprising a clamping block for carrying a clamping block anvil thereon, a pair of coil clamping arms pivoted thereon, and a pair of heaters for blowing hot gases on the anvil, the lead wire coil clamps positioned on the anvil, the coil carried in the open clamps, and the coil clamping arms, to heat said parts to a desired temperature and thus prevent coil fracture during clamping.

A further object is a pair of directed heaters, each comprising a gas burner whose flame burns in a directed funnel projecting therefrom, for directing a portion of the gases of combustion onto the lead wire clamps, the coil positioned thereon, the coil clamping anvil of a clamping device for a filament feeding and filament mounting machine.

Referring to the drawing in which like numerals of reference indicate similar parts throughout the several views:

Fig. 1 is a perspective view of the improved clamping device of our invention at a filament feeding and filament clamping station of an automatic filament mounting machine and showing the delivery of a preformed stem into the coil clamping anvil.

Fig. 2 is a fragmentary perspective view showing the delivery of an incandescent lamp filament into the open clamps of the lead-in conductors of the positioned stem of Fig. 1.

Fig. 3 is a perspective view of a mount having a clamped incandescent lamp filament.

Fig. 4 is a sectional view of a delivery funnel for the burner employed by applicants to heat the clamping block anvil, lead-in wires, clamping anvil and clamping arms during the clamping operation.

Referring to Fig. 1 of the drawing, an improved filament clamping device of our invention for an automatic incandescent lamp mounting machine is designated by the reference numeral 10. This device is mounted, as by brackets or other suitable means (not shown), on the stationary portion of the machine at the filament feeding and filament clamping station. This filament clamping device comprises a stationary mounting block 12, a coil clamping anvil 14 carried on said block, a coil clamping arm lever 15 pivotably mounted on said block 12 and carrying a pair of coil clamping arms 16 and 18, and a coil heating means 20 mounted by means of brackets 22 on the block 12.

The block 12 has an inverted L-shaped lower portion 24, the vertical longer side of which is employed for mounting on the stationary portion of the automatic incandescent lamp filament mounting machine (not shown).

The horizontal shorter portion of the lower portion 24 extends forwardly, as viewed in Fig. 1, and has a bifurcated end 26 which is employed for pivotally mounting the lever 15 as hereinafter explained. An inverted L-shaped upper portion 28 of the block 12 has its horizontal anvil supporting surface 30 extending rearwardly, when viewed in Fig. 1, for supporting the anvil 14 thereon.

This coil clamping block anvil 14 is provided with suitable spaced, downwardly inclined, lead wire guide slots 32, and a vertical axial arbor guide groove 36 in the forward portion of said anvil.

Depending from the guide grooves 32 adjacent the outer wall of each groove is a pair of clamping anvil extensions 38 (Figs. 1 and 2) which extend inwardly, when viewed in Fig. 1, from the grooves 32. These extensions may have vertical guide grooves in their outer-faces for the guided reception therein of the open hooked ends of extremities 42 of leading-in and supporting conductors 44 of a lamp stem 46. In addition to the conductors 44, the stem 46 (Figs. 1 and 3) is provided with an arbor 48 and an exhaust tubulation 49.

Each of the coil clamping arms 16 and 18 is provided with a bending chisel 50 and 52 respectively (Figs. 1 and 2) on its upper extremity for cooperation with stationary clamping anvil extensions 38, as hereinafter explained. The chisels 50 and 52 each have a hook engaging guide slot (Fig. 2) cut in the forward face and are adjustably mounted on bifurcations 54 of the bifurcated upper end of the coil clamping arm lever 15. This lever 15 is pivotally mounted on a pin 58 extending between the bifurcations of the bifurcated end portion 26 of the coil bending block 12.

Coil heating means

The coil heating means 20 are adjustably mounted on each side of the clamping anvil extensions 38 by means of brackets 22, adjustably secured to the under side of the lower portion 24 of the mounting block 12. Each of the heating means 20 may suitably comprise a burner 60 to which a gas and air mixture is fed by means of a suitable inlet pipe 64. The heating ends of the burners 60 are suitably capped with funnels 68 for directing a portion of the combustion gases against the stationary clamping anvil extensions 38, to continuously maintain these parts (by radiation, conduction and convection) at a desired temperature during the filament feeding and filament clamping operation.

In Fig. 2 a transfer arm 72 of a filament feeding mechanism (not shown), provided with a filament carrying nest 74 on its free end, is shown (in its downward vertical travel between the bifurcations 54 of the lever 15) depositing a filament 76 in the open hooks 42 of the leads 44.

Operation

As shown in Fig. 1 stem holding jaws 78 of a stem holding head (not shown) of the automatic mounting machine carries a stem 46 by means of its arbor 48. These jaws 78, and hence the hooked extremities 42 of the stem leads 44 move downwardly into the guide grooves 32 in the anvil 14 (on which the hooks 42 are closed), until the hooks 42 rest in the guide grooves on the heated clamping anvil extensions 38.

It will be understood that simultaneously the lower extremity of the arbor 48 enters the axial guide slot 36 on the end of the anvil 14, thus positioning the stem 46 for the filament feeding and clamping operation. It will be further understood that the lever 15 and hence the coil clamping arms 16 and 18 carried thereon (as shown in Fig. 1) are in the filament loading position, namely, the position furthest away from the heated extensions 38.

After the hooked extremities 42 of the leads 44 have

been positioned on the extensions 38, the transfer arm 72 passes through the bifurcations 54 and the bending chisels 50 and 52 and deposits the filament 76 on the upturned hooks 42. The transfer arm 72 then continues downwardly through the bifurcations 54 of the lever 15 after delivery of the filament 76.

It will be understood that meanwhile during the filament feeding operation the hooked extremities 42 have been heated to the desired temperature by combustion gases emitted from the funnels 68 and conduction, convection and radiation from the extensions 38. Further, in the matter of seconds, the now positioned filament 76 and its legs particularly, become heated to the same desired temperature. At the appropriate predetermined time in the operating index cycle the lever 15 and the hook guide grooves in the arms 16 and 18 carried thereon, are moved forward by cam actuating means (not shown) into contact with the open ends 42 of the leads 44. The arms 16 and 18 press the open ends of the hooked extremities around the filament legs thus locking or clamping said heated and now ductile filament legs therebetween.

Although a preferred embodiment of our invention has been disclosed it will be understood that modifications may be made within the spirit and scope of the invention.

We claim:

1. A filament clamping device for an automatic mounting machine comprising a mounting block, a filament leg clamping anvil mounted on said block and having readily heatable extensions for positioning the filament leg carrying ends of a pair of lamp stem leads thereagainst, an oscillating filament leg clamping lever pivotably mounted on said block for simultaneously engaging and clamping each of said filament carrying ends about a leg of a filament carried therein, and heating means mounted on said block adjacent said anvil in substantially axial alignment with said extensions and for ductilizing said filament carrying ends and filament legs prior to and during filament leg clamping by conduction, radiation and convection.

2. A filament clamping device for an automatic mounting machine comprising a mounting block, a filament leg clamping anvil mounted on said block and having readily heatable extensions for positioning the filament leg carrying ends of a pair of lamp stem leads thereagainst, an oscillating filament leg clamping lever pivotably mounted on said block for simultaneously engaging and clamping each of said filament carrying ends about a leg of a filament carried therein, and heating means mounted on said block adjacent said anvil for ductilizing said filament carrying ends and filament legs prior to and during filament leg clamping by conduction, convection and radiation, said heating means comprising a burner adjacent each of said filament carrying ends and a heat directing funnel appended thereto and in substantially axial alignment with said extensions.
